(57) **CLAIM**

The ornamental design for a litter receptacle, as shown and described.

DESCRIPTION

FIG. 1 is a front perspective view of the litter receptacle; FIG. 2 is a front view thereof;

FIG. 3 is a left side view thereof, wherein the right side view is a mirror image thereof;

FIG. 4 is a top view thereof;

FIG. 5 is a front right perspective thereof;

FIG. 6 is a right side perspective thereof, while the left side perspective is a mirror image thereof; and,

FIG. 7 is a right rear perspective thereof, wherein the left rear perspective is a mirror image thereof.

The broken lines in the drawings are for the purpose of illustrating portions of the litter receptacle, which form no part of the claimed design.
